UNITED STATES PATENT OFFICE.

ANTHONY WALLACE, OF NEW YORK, N. Y.

DRIP-PAN ALARM.

Application filed November 17, 1922. Serial No. 601,519.

To all whom it may concern:

Be it known that I, ANTHONY WALLACE, a subject of the King of Great Britain, and a resident of the city of New York, borough 5 of Manhattan, in the county and State of New York, have invented a new and Improved Drip-Pan Alarm, of which the following is a description.

My invention relates to drip pan alarms 10 adapted to be set on the edge of a pan and more particularly to an alarm operated by a float adapted to cause an audible signal to be sounded.

The general object of my invention is to 15 provide an alarm of the indicated character improved in various particulars with respect to the manner in which the bell clapper is controlled and novel means whereby to unfailingly cause the clapper to be released 20 by the float through the medium of devices involving the minimum number of parts of simple form.

Reference is to be had to the accompanying drawings forming a part of this specification, it being understood that the drawings are merely illustrative of one example 25 of the invention.

Figure 1 is a vertical section of a drip pan alarm embodying my invention applied 30 to a pan shown in part;

Figure 2 is a transverse vertical section on the line 2—2, Figure 1;

Figure 3 is a horizontal section on the line 35 3—3, Figure 1.

In constructing an alarm in accordance 40 with my invention a box or casing 5 is provided with a clip 10 or equivalent means to fit over the edge of the drip pan A. A gong 11 of known form is provided, the 45 numeral 12 indicating the main arbor on which the gong is secured; 13, the clapper carried by the pallet 14, controlling a conventional clock train 15, all of which parts are of known form and arrangement and 50 therefore need no further description.

Mounted on the arbor of the pallet 14 to 55 vibrate therewith is a lateral arm 16 which therefore is subject to the action of the clock train. In order to prevent movement 50 of the arm 16 and therefore hold the pallet 14 and the clock train inactive, I provide above the arm 16 a gravity latch plate 17 hung suitably as at 18 in the casing 5 near the top, said latch plate 17 having a down-turned end adapted to be disposed in front 55 of the arm 16. It will be obvious that with

the latch 17 engaging the arm 16 the clock train cannot function to vibrate the clapper 13 and sound the gong 11.

The float 19 has a stem 20 advantageously 60 disposed obliquely and extending freely through an oblique bearing 21 in the casing 5 so that the float may freely rise and fall with the rise and fall of water in the pan A. The upper end of the float stem 20 is disposed 65 directly beneath the latch 17 and therefore when the float rises the stem 20 will automatically lift the latch 17 out of engagement with the arm 16, thus permitting the pallet 14 to vibrate under the action 70 of the clock spring 22 of the clock train 15. In order to manually control the clapper 13 and provide for resetting the same controlled by the latch 17, I provide a lever 23 fulcrumed at one end on the top of the 75 casing 5 beneath the gong 11 and adapted to be manually moved with the finger to swing the clapper 13 to a position to lock the pallet 14 against vibration so that the gong will not sound when the alarm is 80 detached from the pan A for emptying said pan. When the alarm is replaced on the pan A after the latter has been emptied, the lever 23 is moved away from clapper 13, thereby leaving said clapper subject to 85 the release of the arm 16 by the lifting of the latch 17 by float 19.

By disposing the bearing and stem 21 obliquely the float 19 is brought within the planes of the sides of the casing 5 or substantially so to make for compactness and the angularity of the stem and bearing is not such as to prevent the free movement of the float.

I would state in conclusion that while the 95 illustrated example constitutes a practical embodiment of my invention, I do not limit myself strictly to the exact details herein illustrated, since, manifestly, the same can be considerably varied without departure 100 from the spirit of the invention as defined in the appended claims.

Having thus described my invention, I 105 claim:

1. A drip pan alarm including a casing having means to mount the same on a drip pan, an audible alarm supported by said casing, said alarm including a clock train and pallet, a lateral arm rigid with the pallet, a gravity latch plate hinged at one 110 end in the casing above said arm and having a downwardly directed end normally dis-

posed in front of the path of vibration of said arm to prevent movement of the arm, a bearing in the casing beneath the latch plate, and a float below the casing 5 and having a stem extending through said bearing and adapted to engage said latch plate and disengage the same from said lateral arm with the rising of the float.

2. A drip pan alarm including a gong

and clapper, a clock train to operate the 10 clapper, a lateral arm adapted to vibrate with the clapper, a gravity latch plate to engage said arm and restrain the clock train, a float having an obliquely disposed stem 15 engaging said latch and an oblique bearing in which said stem has movement, said bearing disposed beneath said latch plate.

ANTHONY WALLACE.
